United States Patent Office

Des. 216,253
Patented Dec. 9, 1969

216,253

VEHICLE BODY

Joseph C. Vittone, 4301 Twining St.,
Riverside, Calif. 92502

Filed July 3, 1968, Ser. No. 12,613

Term of patent 14 years

Int. Cl. D12—08

U.S. Cl. D14—3

Fig. 1

Fig. 2

Fig. 3

Fig. 4

Fig. 5

FIG. 1 is a perspective view of a vehicle body showing my new design;

FIG. 2 is a top plan view thereof;

FIG. 3 is a side elevational view thereof;

FIG. 4 is a rear view thereof; and

FIG. 5 is a front view thereof.

The elements shown in broken lines are included for illustrative purposes only.

I claim:

The ornamental design for a vehicle body, substantially as shown and described.
